His Attorney.

UNITED STATES PATENT OFFICE

PERCY S. BAILEY, OF MARBLEHEAD, MASSACHUSETTS, ASSIGNOR TO GENERAL ELECTRIC COMPANY, A CORPORATION OF NEW YORK

FLOOD-LIGHTING DEVICE

Application filed November 17, 1928. Serial No. 320,169.

My invention relates to flood lighting projectors. More particularly it relates to flood lighting projectors of the type which is especially adapted for use in the illumination 5 of fountains.

Among the objects of my invention are the following: to provide an improved adjustable support for a fountain flood light which will be effective whether the flood light is immersed in water or raised above the water; to provide improved means for supporting and adjusting the lamp within the housing of the flood light; and to provide an improved housing with a drain system.

15 However, the invention will be more fully understood from the following specification and claims, reference being had to the accompanying drawing in which Fig. 1 shows a lamp in section and in elevation having the 20 features of the invention; Fig. 2 is a section of the lamp taken on line 2-2, Fig. 1; and Fig. 3 is a section on line 3-3, Fig. 1.

Referring more in detail to the drawing and in particular to Fig. 1, it will be seen 25 that the flood light is provided with a base 2, to which there is secured a hollow rod or pipe 3 in any suitable manner, as for example by means of threads 4, or by means of a set screw 5, or both. In adjustable engagement 30 within the pipe 3 there is provided a second pipe or rod 6. The outer pipe 3 is provided with a tenon in the form of a set screw 7, which extends through the walls of the pipe 3 and into a mortise or slot 8 that extends 35 lengthwise of the pipe 6. Leading off to the right from the slot 8 I provide branches 9, 10, and 11. It will be seen that the branches 9 and 10 are provided respectively with notches 15 and 16 on their upper sides whereas 40 the branch 11 is provided with a notch 17 on the under side. On its upper end the pipe 6 carries the casing 12 of the flood lamp. The casing may be secured to the pipe 6 in any suitable manner. For example, as shown in 45 Fig. 1, the lower part of the casing is provided with a collar 13 into which the end of the pipe 6 projects and to which it is locked by means of a pin 14 extending through both the pipe and the collar.

50 When it is desired to raise and lock the cas-

ing out of the water, the rod 6 is raised and rotated to carry the notch 15 or 16 over the tenon 7 whereupon by releasing the weight of the housing the end of the bolt or tenon will be caught in the notch 17. When the 55 bolt 7 is in the notch 16 or in notch 15 the lamp casing will be high above the water level.

When the casing 12 is immersed in water, the upward pressure of the water will tend to 60 raise it. Therefore, in order to hold the lamp under water it is necessary to carry the notch 17 in branch 11 under the end of the bolt 7 and then releasing the casing. The water will then press the casing upward and cause 65 the end of the bolt 7 to engage the notch under it.

Referring to Fig. 3 the engagement of the inner end of the bolt 7 with the notch 17 is clearly shown. In this figure it is also shown 70 how the bolt 7 is in threaded engagement with the pipe 3 and that the forward end of the bolt is free from threads and can therefore freely slide in any of the channels and engage any one of the notches in the pipe 6. 75 Obviously, in order to disengage the casing from either notch 15 or 16 it is necessary to press up the casing and then rotate it until the end of the bolt 7 reaches the channel 8.

To make the base secure, it is provided with 80 holes 49 in order that it may be bolted to the floor for the fountain.

Within the casing 12 suitable means are provided for supporting the lamp 18 and the supporting socket 19, the latter being provided 85 with terminals 20 and 21 to which the wires of a cable 22 may be connected as shown, for supplying current to the lamp. The head 23 of the lamp socket is bolted to a bifurcated socket element 24 fastened on the upper end 90 of the pipe 25. Pipe 25 is secured in position between the clamping springs 26 and 27, which springs are adapted to be drawn together by means of a bolt 28. The springs 26 and 27 are secured to a plate 29 which is in 95 turn screwed to the lugs 30 at the bottom of the casing 12 by means of screws 31. In order to prevent the tube 25 from turning when the lamp 18 is being screwed or unscrewed in its socket, a groove 32 is provided in the 100

tube 25 which receives the end of a tenon 33. This arrangement serves as a lock and guide for the pipe or rod 25. Tenon 33 is secured to the plate 29 by means of screws 34.

5 In order to protect the cable 22 a water proof conduit is provided which terminates the casing in a water tight connection comprising the plug 22'. Near the bottom of the casing a water tight drain is provided which 10 consists of a conduit 22^a that terminates in a plug 30' similar to plug 22'. The conduit 22^a extends to any point outside the fountain. The object of the drain is to allow any water which may at any time get into the casing to 15 drain off and thus maintain the inside of the casing dry.

Plate 29 bridges the gap between the pair of lugs 30 which gap receives the lower end 20 of the rod 25. The plate 29 is perforated and through this perforation the lower end of the rod 25 extends as clearly shown in Fig. 1. It will be seen therefore that the axis of 25 the perforation coincides with the axis of the shaft 25 and with the longitudinal axis of the flood light. Obviously therefore by sliding the rod lengthwise the lamp 18 may be properly adjusted within the casing 12 and along its axis.

Within the casing 12 there is mounted a reflector 35, which latter is secured along its 30 rim to the casing by means of clamps 36. Between the clamps 36 and the reflector and between the casing 12 and the reflector, gaskets 37 are interposed, one on either side of 35 the reflector. In order to centralize the reflector a ring 38 is provided between the rim of the reflector and the wall of the casing, the ring being mounted on a shelf 39 formed near the rim of the reflector. As shown in 40 Fig. 1, the clamps 36 are provided with heels which engage the ring 38 at a point between the screws 40 and the side of the casing. Along the rim of the casing there is provided 45 a ring frame 41 which holds the lens 42 of the lamp. This lens is secured to the ring frame by means of clamps 43 and screws 44. The clamps 43 are provided at one end with heels that rest on the ring 41 while the inner ends of all rest in engagement with the lens 42. 50 Interposed between the lens 42 and the ring 41 a suitable gasket 45 is used to protect the lens and to provide a water-tight seal between the lens and the ring 41. Between the rim of casing 12 and the ring 41 a gasket 55 46 is provided, the object of which is to render the connection between the two elements water-tight. For clamping the ring to the casing thumb bolts 47 are provided which are pivoted to lugs 48 that project from the 60 outside of the casing 12.

By my invention, I provide an improved form of flood light for a fountain which is easily manufactured, which is rugged and water-proof, which may be kept drained, 65 and which may be readily adjusted either

above the water or under the water without the necessity of handling any clamping devices such as set screws and the like. On the contrary, the device is instantly locked in position by merely allowing it to slide 70 to the proper height and carry the proper notch into engagement with the tenon.

While I have elected to illustrate my invention in connection with a specific form of flood light, it will be understood that I 75 do not wish to be limited to one form inasmuch as I contemplate modifications within the spirit of the invention and the scope of the claims contained herein.

What I claim as new and desire to secure 80 by Letters Patent of the United States, is:

1. In a flood light, a casing adapted to enclose a light source and a reflector therefor, 85 said flood light having within said casing a support for the lamp, said support comprising a rod held in position by and between the arms of a resilient clamp, said clamp being mounted in the casing in position to hold the rod in position along the longitudinal axis of the casing, said rod being provided with a mortise in the form of a slot extending lengthwise, the rod and a tenon supported within the casing with the end thereof in operative engagement with 90 said mortise, whereby the rod may be slid between the arms of the clamp along the axis of the casing but prevented from rotating.

2. In a flood light, a casing adapted to enclose a light source and a reflector therefor, 100 said flood light having within said casing a support for the lamp, said support comprising a rod held in position by and between the arms of a resilient clamp, said clamp being mounted in the casing in position to hold the rod along the longitudinal axis of the casing, said rod being provided with a mortise in the form of a slot extending along 105 the side of the rod and a tenon supported within the casing with the end thereof in operative engagement with said mortise, whereby the rod may be slid between the arms of the clamp along the axis of the casing but prevented from rotating, said clamp and said tenon being mounted on a plate within the 110 casing, the plate extending transverse the axis of the casing, said plate being perforated, the axis of the perforation serving as a guide bearing for the rod in its longitudinal movement, said plate being supported upon lugs near the bottom of the case whereby the rod may project through the perforation and beyond said plate.

In witness whereof, I have hereunto set my hand this 14th day of November, 1928.

PERCY S. BAILEY.
